UNITED STATES PATENT OFFICE.

JERREY MOFFITT, OF SOUTHBRIDGE, MASSACHUSETTS.

MICROMETER-GAGE.

SPECIFICATION forming part of Letters Patent No. 319,919, dated June 9, 1885.

Application filed March 25, 1885. (No model.)

To all whom it may concern:

Be it known that I, JERREY MOFFITT, a citizen of the United States, residing at Southbridge, in the county of Worcester and State 5 of Massachusetts, have invented certain new and useful Improvements in Micrometer Calipers or Gages; and I declare the following to be a description of my said invention, sufficiently full, clear, and exact to enable others 10 skilled in the art to which it appertains to make and use the same, reference being had to the accompanying drawings, which form a part of this specification.

In the construction of micrometer-calipers 15 of the class to which my invention appertains it has heretofore been the practice to form one or more slots in the cylindrical portion which surrounds the gage-screw, so that the sides of said cylinder may be sprung together for taking up the looseness or backlash occasioned 20 by wear on the threads of said gage-screw, and these slots, being more or less open when the screw is run out, afford a passage through 25 to the interior of the cylinder, find lodgment upon the screw-threads, and by their gritty action greatly increase the abrasion and wear on the threads, so that in a comparatively short time the perfection and accuracy of the instrument is destroyed, as a slight variation or 30 irregularity will throw the indicating-lines out of proper relation, and thus render the tool practically worthless for denoting the very fine measurements and gagings for which it is intended.

The objects of my present invention are, to afford facilities for tightening the grip upon the gage-screw threads, and to avoid the necessity of a split or division in the cylinder 40 or part of the frame which surrounds said gage-screw, thus obviating the liability of dust, dirt, or filings entering and wearing out the threads; also, to provide a construction of the step-screw that will permit of said screw being more accurately maintained in exact alignment 45 with the gage-screw under all conditions of adjustment, so that the faces of the two screws will stand in accurate relation to each other when turned from their original positions. These objects I attain by constructing 50 the instrument in the peculiar manner hereinafter described and claimed.

In the drawings, Figure 1 is a side view of a micrometer caliper or gage embracing my invention. Fig. 2 is a longitudinal section 55 through the frame and screw cap or sheath. Fig. 3 shows a side and end view of the adjusting ring or nut, and Fig. 4 is a modification of the same.

In referring to parts, A denotes the U-shaped 60 frame provided with the cylindrical extension A', through which the micrometer-gage screw B is arranged. Said cylinder is formed solid or without the usual slot or division, and has within its outer end a slightly tapered female 65 thread at a. The gage-screw B is made of ordinary form, with a spindle or unthreaded portion guided in the frame at f, and with an overhanging cap or sheath, E, that covers the cylinder A' in the usual manner, and which is 70 milled at the head to facilitate turning the screw. The indicating-gaduations are formed on the side of the cylinder A' and on the end of the sheath E in the usual manner. A conoidal nut or thimble, D, having screw-threads 75 on its exterior and interior, and having a slit at one side, as at d, is fitted within the threaded end of the cylinder A' around the gage-screw B, the external thread of said nut fitting the thread of the cylinder, and the internal thread 80 of said nut fitting the thread of the screw B. Both threads of the nut are of the same pitch or number of threads to the inch. The upper end of the nut that projects from the cylinder is milled, as at e, or fitted so that it can 85 be turned conveniently when the outer cylindrical sheath or cap, E, is raised or run out. By turning said tapered nut D down into the tapered end of the cylinder the diameter of the thimble or nut is contracted to take up the 90 backlash or wear, and cause it to grip more tightly upon the screw B, and vice versa. The sheath E fits closely the exterior of the cylinder A', and the smooth spindle of the screw 95 closely the opening in the frame at f, and as there is no slot in the side of the cylinder the screw-threads are completely protected from the entrance of dirt. When the thread of the screw B and nut D become worn out beyond the limit of adjustment, so as to occasion inaccuracy in the gage, the instrument can be renewed by simply replacing the nut or thimble D with a new nut of slightly greater thickness, thus avoiding the necessity of procuring 100

an entire new instrument. The step-screw I is made with a shoulder, as indicated, the point *i* being turned down cylindrical to a size corresponding with the smooth part of the screw 5 B, and the threaded portion *i'* being of larger diameter. The hole J, through the step of the frame A, is bored out to correspond in alignment and axial relation with the hole *f*. The lower part of the hole J is then counterbored, 10 and its thread cut with a tap having a leader that extends up through the hole *f*. It sometimes becomes necessary to rectify the gage by setting the step or anvil I slightly in or out. If the step is simply screwed through the 15 frame and depends on the screw-thread for keeping its end in central alignment, it is very liable to be finished with a greater or less degree of eccentricity or slight inclination, so that the slight turning of the step-screw I, instead of rectifying the instrument, simply throws its point out of position. By the construction herein shown the part of the hole which retains the point *i* central is made 20 smooth and cylindrical and in accurate alignment with the hole in which the micrometer-spindle B moves, so that if the step I is turned it simply revolves about an axis that is in exact line with the axis of said spindle, while the screw-thread, being in the enlarged part, 25 and being formed in a counterbore following the axis of both the openings *f* and J, will have no chance to exert an eccentric action tending to throw the point of the step to one side of its original position or its face out of 30 proper relation with the face of the spindle B, but will simply move the part in and out in direction exactly coincident with the axes of the parts B and I, and after the meeting 35 faces or points of the two screws B and I have been squared to each other they are not sub-

ject to deviations from accuracy by the turning of said screw on its axis to give adjustment of distance between the points.

As a modification in construction, the nut or ring D and interior of the cylinder A' may 45 be made with a straight threaded portion, and a smooth conical part, *m*, below the thread, as indicated in Fig. 4. I prefer, however, the form first above described.

What I claim as of my invention, and desire 50 to secure by Letters Patent, is—

1. The tapered nut or ring D, externally and internally screw-threaded, and having the slot *d*, in combination with the gage-screw B and the frame A, having the cylindrical internally-threaded extension A', substantially as set forth.

2. The combination, with the frame A and micrometer-gage screw B, of the screw I, having the reduced portion *i* and threaded portion *i'*, fitted into the step of the frame in the manner shown and described.

3. In a micrometer caliper or gage, the combination of the gaging-screw B, having the smooth guiding portion and threaded portion, 65 the U-shaped frame A, with the internally-threaded unslotted cylindrical extension A', the conoidal double-threaded thimble-nut D, supporting said screw within the cylindrical extension, and the step-screw I, having the reduced portion *i* and the threaded portion *i'*, fitted to said frame, substantially as set forth.

Witness my hand this 19th day of March, A. D. 1885.

JERREY MOFFITT.
